Primary Examiner — John R Yeh*(74) Attorney, Agent, or Firm* — Nelson Mullins Riley & Scarborough LLP; Thomas J. Engellenner; Reza Mollaaghbabab(57) **CLAIM**

We claim the ornamental design for a disposable mop overlay of absorbent material, as shown and described.

DESCRIPTION

FIG. 1 is a perspective view taken from the front, top, and left perspective of an absorbent pad as a disposable mop overlay of absorbent material showing our new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.
